DESIGN FOR A BRASSIÈRE OR SIMILAR ARTICLE

Morris Bienenfeld, New York, N. Y.

Application December 4, 1939, Serial No. 88,672

Term of patent 7 years

To all whom it may concern:

Be it known that I, Morris Bienenfeld, a citizen of the United States, residing in New York city, in the county of New York and in the State of New York, have invented a new, original, and ornamental Design for a Brassière or Similar Article, of which the following is a specification, reference being had to the accompanying drawing, forming part thereof.

The single figure is a perspective view of a brassière embodying my new design. The back of the brassière is of conventional configuration.

I claim:

The ornamental design for a brassière or similar article, substantially as shown and described.

MORRIS BIENENFELD.
